VALVE LUBRICATING DEVICE FOR
COMBUSTION ENGINES

William A. Black, Toronto, Ontario, Canada

Application November 13, 1933, Serial No. 697,713
In Canada December 22, 1932

4 Claims. (Cl. 123—196)

The principal object of this invention is to eliminate the difficulty met with incident to the adequate lubrication of valve members in an internal combustion engine and to provide an improved form of device for this purpose which will provide for the introduction in the combustion zone of the engine of a lubricant, the quantity and character of which may be accurately controlled in accordance with requirements.

10 A further and important object of the invention is to provide a device of this kind for the introduction of a humidifying medium in regulated proportions along with the lubricating medium and to provide a construction which may be 15 readily adjusted to control the relative proportion of the lubricating and humidifying medium entering the combustion zone.

The principal feature of the invention consists in the novel construction and arrangement of 20 parts wherein air having in suspension a lubricating medium, is directed to the combustion zone through a regulating valve and air, steam or water vapour is associated therewith under the accurate control of a second control valve where- 25 by a humidified lubricating vapour of accurately controlled proportions is provided.

In the drawing, Figure 1 is a mid-sectional elevational view through a device constructed in accordance with the present invention.

30 Figure 2 is a mid-sectional elevational view taken on the line 2—2 of Figure 1.

Figure 3 is a sectional plan view taken on the line 3—3 of Figure 1.

35 Figure 4 is a diagrammatic elevational view of an installation in keeping with the present invention.

Various forms of devices have been devised from time to time for introducing a humidified supply of air directly into the intake manifold 40 and combustion zone of an internal combustion engine. It has also been proposed to provide a receptacle of lubricating oil through which air is drawn and conducted directly to the intake manifold of the engine.

45 The present invention proposes a distinct advance in the art over these previous isolated practices in the provision of a unitary construction which will not only provide for adequate "top" lubrication for a combustion engine, but to provide in conjunction therewith a means of controlling the humidity of the oil-charged vapour entering the combustion zone whereby the efficiency of the engine will be doubly enhanced.

In the form of construction illustrated herein 55 I propose to provide a hollow dome-shaped fit-

ting preferably in the form of a casting 1 having a threaded boss extension 2 at one side which is adapted to be threaded into the intake manifold of a combustion engine or suitably connected therewith by a length of tubing.

The dome-shaped casting 1 has preferably formed integral therewith a central transverse wall 3 and a passage 4 extends inwardly through a boss 2 to merge substantially centrally of the casting with an enlarged passage or bore 5 which extends out through the boss 6 of the casting.

The passages 4 and 5 are thus subject to the vacuum condition existing in the intake manifold of the engine.

A container 7 is detachably connected at 8 to the downwardly extending annular flange 9 of the casting and is adapted to be filled with a suitable quality of lubricating oil or liquid.

A tube 10 open at its outer end to atmosphere is supported at its upper end in the casting 1 and extends downwardly within the container 7 to a point adjacent the bottom thereof and is adapted to admit air into the body of lubricating liquid within the container 7 at the bottom thereof so that air is broken up into fine bubbles and charged with oil vapour.

The amount of air entering the tube 10 is under the accurate control of a valve member 11 threaded axially of the casting 1 and having its lower end cooperating with the valve passage 12 which extends through the bottom of the wall connecting the passages 4 and 5 with the interior of the receptacle 7. Thus by regulating the valve 11 an accurate supply of the amount of oil-charged air entering the passages 5 and 4 to be carried to the intake of the engine may be accurately regulated.

Threaded into the boss 6 is a T-shaped fitting 13 having a passage 14 seated at 15 for co-operation with a needle valve 16 threaded into the fitting. The lower branch 17 of the fitting preferably has threaded thereto a fitting 18 having an enlarged seat at the upper end against which the ball valve 19 is adapted to seat by gravity.

According to the present invention it is proposed to connect the interior passage of the fitting 18 either with the vapour space in the upper chamber of a radiator or with a suitable steam generating device, so that while the engine is operating a constant source of steam or heated water vapour will be available and the association of this medium will be under the accurate control of the valve member 16 so that it will be observed that an accurate control of

the humidity of the oil-charged vapour entering the engine is provided for in this construction, or the inflow of air may be regulated.

The heat of the humidified charge permitted 5 to pass the valve 16 is imparted to the air-borne lubricant within the enlarged chamber 5 and during its passage through the passage 4 to the intake manifold, the lubricating medium will be sufficiently broken up so that it will be distributed uniformly over the surfaces with which it 10 comes in contact.

It will be noted that the casting or fitting 1 in being dome-shaped provides at all times a reservoir chamber above the level of the liquid in 15 the receptacle 7 in which will be contained a volume of oil-charged air, and since the passage 12 draws its supply from this reservoir chamber, an adequate and uniform supply of the lubricant to the engine will be ensured.

20 A device such as described is extremely compact and efficient in its operation, and while in the drawing I have shown a preferred form of the invention, it will be understood that many structural alterations may be made in the carrying out of the invention without departing 25 from the essential spirit thereof.

It will be understood that the fitting 18 instead of being connected to the radiator system of the car or to a heat generator as defined to 30 receive both heat and vapour, may be connected in certain cases with any suitable means by means of which a charge of moisture with or without the application of heat may be introduced into the passage 5.

35 What I claim as my invention is:—

1. A combined lubricator and humidifier for internal combustion engines, comprising in combination, means for containing a supply body of lubricating oil, means releasing a flow of air into the body of lubricating oil to absorb therefrom a vapour charge, a valve controlled passage conducting oil-charged vapour from said supply to the intake manifold of the engine, and a valve controlled means introducing a regulated quantity of humidified air into said passage to further vaporize and humidify the said oil charged vapour.

2. A combined lubricator and humidifier for

internal combustion engines, comprising in combination, a receptacle adapted to contain a supply of lubricating oil, means closing said receptacle and forming therewith an enlarged vapour reservoir above said supply, said means having a 80 valved passage leading to the intake of the engine, and receiving a regulated supply of oil vapour from said reservoir, and means introducing a separate heated humidified air charge in regulated quantities into said passage to mingle 85 with and humidify the oil vapour therein.

3. A combined lubricator and humidifier for internal combustion engines, comprising an inverted cup-shaped casing having an outlet passage for connection with the intake manifold 90 of an engine, an oil receptacle detachably secured to the rim of said inverted cup-shaped fitting having its interior communicating with the interior of said inverted cup-shaped fitting, said fitting having a duct connecting said outlet passage with the interior of the oil receptacle and cup, a valve controlling said duct, a valve fitting mounted on said cup-shaped fitting and adapted to be connected with a source of steam or humidifying vapour, said valve fitting having a valve 95 therein for controlling the supply of the humidifying medium and said outlet passage being connected with said valve fitting to receive said humidifying medium.

4. A combined lubricator and humidifier for 105 internal combustion engines, comprising in combination an inverted dome-shaped cup member having a boss extension on one side for connection with the intake of the engine, said cup-shaped member having a wall internally extending 110 from side to side in alignment with said lug extension, said wall having a passage extending through said lug extension and merging substantially centrally of the cup-shaped fitting with an enlarged mixing passage, an oil receptacle 115 detachably secured to the rim of said cup, said wall having a duct connecting the interior of said oil receptacle with said respective passages, a valve threaded into said wall of the cup and controlling said duct, and valve means controlling 120 the entrance of a humidifying agent into said enlarged passage.
